SWING

George H. Hutaff, Jr., Wilmington, N. C.

Application January 24, 1939, Serial No. 252,651

4 Claims. (Cl. 155—65)

My invention relates to new and useful improvements in swings and while primarily intended as a toy might be adapted for playgrounds or other places of amusement by increasing the dimensions of the several parts.

The principal object of the invention resides in the provision of novel means for suspending or supporting a swing or swings and means for operating the same, said operating means being shown as manual, but it will be understood that other power means might be provided if found desirable or advantageous.

A further object of the invention consists in the provision of novel means for suspending or supporting a swing or swings and for operating the same, the operating means forming a part of the suspending or supporting means and the swing or swings being carried by the suspending or supporting means when the same is operated and further adapted for movement independent of the suspending or supporting means.

A still further object of the invention resides in the provision of a novel frame structure which carries or supports the swing suspending or supporting means, the frame structure having connected thereto a canopy or awning, this canopy or awning, where the swing or swings are adapted for use as a toy forming an ornamentation and giving a neat appearance to the structure as a whole and when the swing or swings are of a size for use at playgrounds or other places of amusement providing protection to the occupants of the swing or swings from the sun or rain.

With the above and other objects in view, which will appear as the description proceeds, my invention consists in the novel details of construction, and arrangement of parts, described in the following specification and illustrated in the accompanying drawing, and while I have illustrated and described the preferred embodiments of the invention, as they now appear to me, it will be understood that such changes may be made as will fall within the scope of the appended claims.

In the drawing:

Fig. 1 is a front elevation with parts broken away.

Fig. 2 is an end elevation.

Fig. 3 is a longitudinal vertical section with parts broken away and parts shown in elevation.

Fig. 4 is a section on the line 4—4 of Fig. 3, looking in the direction of the arrows; and

Fig. 5 is a section on the line 5—5 of Fig. 3 looking in the direction of the arrows.

In carrying out my invention I provide a frame structure which includes the base 1, the standards or uprights 2 and 3, and the strip or bar 4, secured to and connecting the upper ends of the standards or uprights. The base 1, along its front and rear edges, is formed with a depend-

ing flange 5 which is adapted to rest upon the ground or other surface. The bottom edge of each of the standards or uprights is formed with a depending projection 6 and the inwardly directed horizontal flange portions 7 which extend beneath the base 1 and are secured thereto by the nuts and bolts 8 or other suitable means. It will be noted that the depending projections 6 are of a height equal to the height of the flanges 5 and also engage the ground or other surface as is quite clearly illustrated more particularly in Figs. 2 and 3 of the drawing. The upper end of each of the standards 2 and 3 is bent inwardly, as shown at 9, and then outwardly to provide a flange 10, these flanges 10 in turn engaging tongues or projections 11 struck from the strip or bar 4, as shown more particularly in Figs. 3 and 4 of the drawing. It will be noted that the strip or bar 4 is of channel formation and that the tongues or projections 11 are struck from the depending flange portions thereof and extend inwardly, as shown more particularly in Fig. 4 of the drawing. The flange portions 10 of the standards or uprights will engage between the upper surface of the strip or bar 4 and the inwardly directed tongues or projections 11.

At its ends the strip or bar 4 is bent downwardly, as indicated at 12, and the ends of these downwardly bent portions are curled upwardly to provide the eyes 13. Supported in the eyes 13 are the ends of a wire frame indicated at 14, said wire frame being of the shape shown and providing a support for the awning or canopy indicated generally at 15 and which may be made of any material suitable for this purpose.

Adjacent its upper end each of the standards or uprights 2 and 3 is formed with an elongated opening 16, through which extends a horizontal rod 17, this rod 17 extending between the standards or uprights 2 and 3, as more particularly disclosed in Fig. 3 of the drawing, and adapted for free horizontal movement in the openings 16 in a manner as will be presently described. That end of the rod 17, which passes through the opening 16, in the standard or upright 2, is formed with the downwardly projecting extension 18, the lower end of which is bent inwardly to form a projection 19 which is received in an opening 20 formed in the upright or standard 2. That end of the rod 17, which passes through the elongated opening 16, in the standard or upright 3, is formed with the downwardly projecting extension 21, the lower end of which is bent inwardly to form the projection 22 which passes through an opening 23 formed in the standard or upright. A forwardly projecting portion 24 is formed on the extension or projection 22 and the end of this forwardly directed extension is bent at right angles to provide the horizontal portion 25 which

extends in front of the forward edge of the standard or upright 3 and parallel with the extension or projection 22. On this horizontal portion 25 is a rearwardly extending projection 26 which extends parallel with the portion 24. It will be noted that the extensions 19 and 22, received in the openings 20 and 23 respectively, form means for pivotally connecting the horizontal rod 17 to the standards or uprights 2 and 3 and the horizontal portion 25 forms a handhold, or engaging portion for swinging the rod 17 in a horizontal plane towards the forward ends of the elongated openings 16, this forward position of the rod and integral depending portions 18 and 21 being shown by dotted lines 27 in Fig. 2 of the drawing. Each of the standards or uprights 2 and 3 is formed with an inwardly directed flange or projection 28 and to each of these projections is connected one end of a coiled spring 29, the opposite ends of the coiled springs being connected to the horizontal rod 17 to normally hold the same in engagement with the rear ends of the elongated openings 16, as shown more particularly by full lines in Fig. 2 of the drawing. It will be understood that when the rod 17 is swung to the dotted line position, shown at 27, that the springs 29 will expand and will return the rod to its normal position after the manipulating means is released.

The body portions of the swings are shown at 30 and are in the form of boats or tubs. These body portions 30 are suspended from the horizontal rod 17 by means of the cables 31, the cables being formed at their upper ends with eye portions 32 through which the rod extends as is quite clearly illustrated in Fig. 3 of the drawing. Spacer sleeves 33 are received on the rod 17 and properly position the cables 31 so that the body portions of the swings will not contact or rub when swung. These spacer sleeves may be secured to the rod in proper position, in any desired manner. It will be understood that any number of swings may be suspended from the rod 17 and while I have illustrated three suspended swings it will be understood that the number may be increased or decreased as may be desired. When the device is in the form of a toy suitable figures, as dolls or other images may be placed in the body portions 30, but if the device is of a size for use at playgrounds or other places of amusement it will be understood that children or adults may occupy the swings.

From the above detailed description it is thought that the construction and operation will be understood. Normally the parts will be in the position shown in Fig. 1 of the drawing and in full lines in Fig. 2. With the swings occupied the operator will engage the horizontal portion 25, of the depending portion 21 of the rod 17, and when the same is pushed downwardly the rod and the depending portions 18 and 21 will be swung into the dotted line position 27 of Fig. 2, the rod 17 moving to the forward ends of the openings 16. This forward movement will carry the swings forwardly into the dotted line position shown at a and when the portion 25 is released the rod 17 will be drawn into its normal rearward position by means of the coiled springs 29. It will be seen that the swings are carried forwardly and rearwardly with the

rod 17 but upon continued manipulation the swings may have movement independent of the rod 17 and will swing forwardly, as shown by dotted lines at a and rearwardly, as shown by dotted lines at b in Fig. 2. The distance of movement of the swings, relative to the rod 17, will be determined by the momentum caused by the operation, and as the swings have independent movement of the rod 17 the individual swings will move different distances or in other words there is no uniform movement of the swings in their independent movement on the rod 17. I wish to lay particular stress on the fact that while the swings are suspended from the rod 17 and move therewith, as the rod is moved forwardly and rearwardly in the elongated openings 16 the swings nevertheless have independent movement and on manipulation the distance of movement is not necessarily uniform but one swing may move to a greater height than another. This, of course, affords amusement to the operator and to the occupants when the device is of such a size as to be used at playgrounds or other places of amusement.

Having fully described my invention what I claim as new and desire to secure by Letters Patent is:

1. A device of the character described including a frame structure having uprights each provided with an elongated opening, a supporting member adapted for swinging movement in the elongated openings, depending extensions on the supporting member extending parallel with the uprights, said depending extensions being pivotally connected to the uprights, a forwardly directed portion formed on one of the depending extensions, said forwardly directed portion adapted to be engaged to swing the supporting member, and a swing carried by the supporting member and adapted for movement therewith and independent movement relative thereto.

2. A device of the character described including a frame structure having uprights each provided with an elongated opening, a member pivotally connected to the uprights and having a portion extending into and adapted for swinging movement in said elongated openings, and a swing carried by the pivoted member for movement therewith.

3. A device of the character described including a frame structure having uprights each provided with an elongated opening, a member pivotally connected to the uprights and having a portion extending into and adapted for swinging movement in said elongated openings, and a swing carried by the pivoted member for movement therewith and independent thereof.

4. A device of the character described including a frame structure having uprights each provided with an elongated opening, a supporting member adapted for swinging movement in the elongated openings, depending extensions on the supporting member extending parallel with the uprights, said depending extensions being pivotally connected to the uprights, a forwardly directed portion formed on one of the depending extensions, said forwardly directed portion adapted to be engaged to swing the supporting member, and a swing carried by the supporting member and adapted for movement therewith.
